[57] CLAIM

The ornamental design for a combined watering can
and misting unit, as shown and described.

DESCRIPTION

FIG. 1 is a right side elevational view of a combined
watering can and misting unit showing my new design,
the left side being a mirror image;

FIG. 2 is a top plan view thereof;

FIG. 3 is a front elevational view thereof;

FIG. 4 is a rear elevational view thereof; and,

FIG. 5 is a bottom plan view thereof.

FIG. 1

FIG. 2

FIG. 3

FIG. 4

FIG. 5
